UNITED STATES PATENT OFFICE.

FREDERICK SEABERG, OF CHICAGO, ILLINOIS, ASSIGNOR TO NATIONAL DUMP CAR COMPANY, A CORPORATION OF MAINE.

DUMP-DOOR-OPERATING MECHANISM.

937,100.

Specification of Letters Patent. Patented Oct. 19, 1909.

Application filed February 6, 1909. Serial No. 476,522.

To all whom it may concern:

Be it known that I, FREDERICK SEABERG, a citizen of the United States, residing at Chicago, in the county of Cook and State of Illinois, have invented certain new and useful Improvements in Dump-Door-Operating Mechanism, of which the following is a specification.

One of the objects of my invention is to provide a dump door mechanism especially adapted for use in connection with flat bottom cars provided with drop doors, in which provision is made for carrying the contents of the car when discharged beyond the track rails. The invention, however, is applicable to cars of other types, and will serve the same useful function in all cases where it is desired to carry the discharged load beyond the point where it would fall if the dump doors were pivoted upon fixed hinges.

Another object of my invention is to provide a chain operated door with positive means for retaining the door in closed position and relieving the chains from strain when the doors are closed.

Other and further objects and advantages of my invention will appear from the following description and claims, taken in connection with the accompanying drawings, in which—

Figure 1 is an end view partially in section of a car equipped with one specific embodiment of my invention. Fig. 2 is a view similar to Fig. 1, showing the dump doors open. Fig. 3 is a side elevation of part of the car shown in the preceding views. Fig. 4 is a fragmentary side elevation of part of the car showing the door raising mechanism. Fig. 5 is a section on the line 5, 5 of Fig. 4. Fig. 6 is a section on the line 6, 6 of Fig. 5, showing the bearing of the winding shaft in the cross member of the car underframe. Fig. 7 is a section on the line 7, 7 of Fig. 5.

The car illustrated is provided with a center sill composed of channels 1, 1 connected by cross members 2, 2. Superposed upon the center sill are cross bearers 3 supporting at their outer ends the sides 4 of the car. At the base of the car sides and resting upon the cross members 3 are angle irons 5, and angles 6, 6 are secured along the upper edges of each of the cross members. A longitudinal

floor plate 7 occupies the central portion of the car. The spaces formed by the members above mentioned are filled by dump doors 8 hinged adjacent the longitudinal center of the car.

It will be obvious that the application of my invention is not dependent upon any particular form of car underframe, other than that provision must be made for unobstructed door openings.

Each of the dump doors 8 is connected to the underframe of the car by pairs of links 9, 10. In the present instance, these links 65 are pivoted at their outer ends to the door 8 and at their inner ends to transverse angles 11 riveted to the top of the center sill. As clearly shown in Figs. 1 and 2, the length of the links 9, 10 and their points of attachment 70 to the center sill structure and to the doors are so proportioned and arranged that the links do not lie parallel but are disposed at an angle to each other. The outer link 9 is of considerably greater length than the inner 75 link 10, whereby an outer thrust is imposed upon the door when its free edge is lowered, thereby carrying said free edge outward toward the side of the car sufficiently to insure the discharge of the load beyond the track 80 rail.

The longitudinal central floor plate 7 occupies a position above the inner edges of the dump doors 8, and the hinge links of the dump doors and the operating mechanism 85 therefor are so disposed that when the door is closed it lies snugly beneath the horizontal flanges of the angles 6, the central floor plate 7 and the angles 5 at the foot of the car sides.

For the purpose of operating the doors, I provide winding shafts 12 rotatably mounted at the sides of the car beneath the floor level. The shafts 12 are preferably square in cross section and are provided with bushings 30 fitted thereto and rotatably mounted in bearings 31 secured to the cross members of the car. Winding chains 13 are secured at one end to said shaft 12 and at the opposite end to the doors 8 adjacent their outer edges. For the purpose of rotating the winding shaft 12 to close the doors, I provide any suitable form of operating mechanism at the ends of the car. In Fig. 1, a suit-

able operating lever 14 is shown, the same being pivotally mounted upon the shaft 12. The operating lever carries a reversible pawl 15 adapted to engage a pinion 16 secured to the operating shaft 12. By means of the reversible pawl 15 such shaft may be turned in either direction. The reversible pawl 15 is also shown in Fig. 3, together with a second pinion 17 also secured to the shaft 12, the latter pinion being engaged by a detent 18 mounted upon the end of the car and adapted to hold the shaft 12 against rotation when desired. Preferably, there are four shafts 12, each extending from one end of the car to the center thereof, and each operating half of the doors upon one side of the car. For the purpose of relieving the chains 13 from strain when the doors are closed, I secure to the shafts 12 pinions 19 adjacent the free edge of each of the dump doors, and upon the outer edge of each of the dump doors, I secure coacting racks 20 formed upon castings 21 riveted to the under side of the dump doors. As illustrated, the operating chains 13 are preferably connected to the doors 8 through the castings 21, said castings being provided with a downward projection in which an aperture 22 is formed, and with a laterally extending web 23 through which an eye-bolt 24 extends. The chain 13 is passed through the aperture 22 and its end link engaged with the eye of the eye-bolt, the latter being held in place by a nut 25 above the web 23. The rack 20 inclines upwardly and inwardly from the free edge of the door. Upon winding the chain upon the shaft 12 the doors will be raised from the position shown in Fig. 2 to that illustrated in Fig. 1, and as the doors approach the closed position, the racks 20 will engage the pinions 19, whereupon movement will be communicated directly from said pinions to the door, and owing to the inclination of the racks 20, the upward movement of the doors after their racks engage said pinions will be accompanied by an inward thrust which will bring the links 10 to a vertical position, as illustrated in Fig. 1. Upon rotating the shafts 12 in transverse direction, the doors will be permitted to drop and will assume the position illustrated in Fig. 2.

I will have it understood that I do not desire to limit myself to the precise construction and arrangement of parts shown in the drawings and herein described, as various modifications or alterations may be made without departing from my original invention as defined in the appended claims. For instance, the inclination of the racks 20 is necessary only in connection with the idea of so mounting the doors that they will move bodily outward when opened to clear the track rails. Such inclination would not be

necessary in connection with a door having a simple concentric movement upon an ordinary hinge joint.

It is obvious that other variations from the specific structure illustrated would be included within my invention. 7

I claim:

1. In a car, a floor provided with a door opening, a dump door mounted at one edge of said opening to have a pivotal movement with respect to the door opening and a bodily movement transversely thereof, a pinion beneath the floor adjacent the opposite edge of said door opening, a rack on the door operatively related to said pinion, and means for raising the door. 80

2. In a car, a floor provided with a door opening, a door, a link pivoted at one end to the car frame adjacent one edge of said door opening and at the other end to said door, a pinion beneath the floor adjacent the opposite edge of said door opening, a rack on the door operatively related to said pinion, and means for raising the door. 85

3. In a car, a floor provided with a door opening, a door, a pair of links adjacent one edge of said opening, each pivoted at one end to the car frame and at the other end to said door, said links being angularly disposed with relation to each other, and means adjacent the opposite edge of said opening for raising said door. 90

4. In a car, a floor provided with a door opening, a door, a pair of links adjacent one edge of said opening, each pivoted at one end to the car frame and at the other end to said door, said links being angularly disposed with relation to each other, a pinion beneath the floor adjacent the opposite edge of said door opening, a rack on the door operatively related to said pinion, and means for raising the door. 105

5. In a car, a floor provided with a door opening, a dump door mounted at one edge of said opening to have a pivotal movement with respect to the door opening and a bodily movement transversely thereof, a pinion beneath the floor adjacent the opposite edge of said opening, an inclined rack on the door operatively related to said pinion, and means for raising the door. 110

6. In a car, a floor provided with a door opening, a dump door mounted at one edge of said opening to have a pivotal movement with respect to the door opening and a bodily movement transversely thereof, a winding shaft beneath the floor adjacent the opposite edge of said opening, a pinion secured to said shaft, a chain extending from said shaft to the free edge of said door, a rack upon said door adjacent its free edge, and means for rotating said shaft. 120

7. In a car, a floor provided with a door opening, a door, a pair of links adjacent one

edge of said opening, each pivoted at one end to the car frame and at the other end to said door, said links being angularly disposed with relation to each other, a winding shaft 5 beneath the floor adjacent the opposite edge of said opening, a pinion secured to said shaft, a chain extending from said shaft to the free edge of said door, a rack upon said

door adjacent its free edge, and means for rotating said shaft.

In testimony whereof, I have subscribed my name. ¹⁰

FREDERICK SEABERG.
